Application August 15, 1939, Serial No. 290,311

8 Claims. (Cl. 255—46)

The present invention relates to an improved earth drill which is particularly adapted for the high speed drilling of exploration and blasting holes through rock and the like.

In the drilling of rock, the most commonly used "bit" consists of a matrix or form in which there are set a plurality of cutting diamonds which serve as cutting and abrading edges to wear away the rock as the drill is rotated. In order to drill satisfactorily with diamond drills, it is necessary to provide a continuous stream of water at the drill "bit" and to this end it has been customary to use a hollow drill rod and drill spindle through which water is forced to the bit while it is being rotated.

The water supply to the hollow drill spindle is normally made through a rotatable connection which is attached to the upper end of the drill rod.

In the drilling of deep holes, particularly in close quarters as where the drilling is being done within the close confines of a mine, it is necessary to use a drill rod composed of many sections, each of the sections being from 20 to 60 inches long, depending upon the working space available.

According to previous drilling practice, it has been customary to use a drilling machine having a hollow spindle through which the drill rods are advanced, each new section of drill rod being attached to the preceding sections above the machine and advanced through the machine as the drilling proceeds until finally the desired hole depth is obtained.

As explained above, the water connection is at the upper end of the hollow drill rod and hence in order to add each new section to the drill rod, it has been necessary to disconnect the water swivel from the drill rod, then add the additional section and finally again reconnect the water swivel for further drilling operations.

Time studies have indicated that frequently as much as 80% of the total operating time of the machine is consumed in the non-productive operations of adding the drill rod sections, connecting and disconnecting the water swivel, unchucking and rechucking, running the drill spindle back, and the like, only 20% of the total time being used in actual drilling operations.

It is an object of the present invention to provide an improved drilling apparatus in which the time which must be consumed in non-productive operations is greatly reduced.

It is a further object of the invention to provide an improved drilling apparatus which is capable of much higher speeds than those heretofore obtainable, and capable of rapid connection and disconnection of the drill rod for the insertion and removal of drill rod sections.

It is also an object of the invention to provide

a drilling apparatus in which the drill rod sections may be connected and disconnected by power means obviating the use of hand tools for tightening and loosening the joints in the drill rod sections.

It is a further object of the invention to provide an improved drilling machine in which, if desired, the raising and lowering of the drill rod spindle may be accomplished with great rapidity, or when desired slight movements completely under direct control of the operator may be accomplished during connecting and disconnecting operations of the drill rod.

It is a further object of the invention to provide an improved drilling apparatus in which the drill rod in the hole may quickly and firmly be held against movement during the connecting and disconnecting operations and then quickly released for the ensuing drilling operation.

It is a further object of the invention to provide an improved drill rod gripping apparatus capable of use with the drill at any angle and in which regardless of the angle of drilling, the aforementioned rapid connection and disconnection of the drill rods may be accomplished.

Other objects of the invention are those inherent in and implied by the method and apparatus herein illustrated, described and claimed.

The invention is illustrated with reference to the drawings in which Figure 1 is a side elevational view partly in section of the drilling apparatus.

Figure 2 is an end elevational view in the direction of arrows 2—2 of Figure 1.

Figure 3 is a sectional view along the line 3—3 of Figure 2.

Figure 4 is a side elevational view partly in section of the drilling apparatus, the upper section portions being taken along the line 4—4 of Figure 2, and the lower sectional portions being taken along the line 5—5 of Figures 2 and 3.

Throughout the drawings, like numerals designate corresponding parts.

The illustrated embodiment of the present invention includes a motor device M, which rotates in one direction, a gear box device G, which transmits the power of the motor in either direction of rotation and a drill D, which is the driven unit. In Figure 1, these parts are shown beneath the brackets designated M, G and D respectively. The motor M and gear box G may be separate, or unitary devices the desideratum being rotary motion of the requisite horsepower available in either direction of rotation. The horsepower required varies widely from a few horsepower for shallow small diameter drilling to upwards of 20 horsepower and in some instances even more, for large diameter deep hole drilling. It is usually more convenient to use

a unidirectional air motor or internal combustion engine, and a forward and reverse gear, but where electricity or steam is available reversible motive power units are more convenient.

In the illustrated embodiment of the invention the motor mechanism M is a positive displacement pneumatic motor 10 which is supplied by an air feed line 11, having a throttle valve 12 therein.

The motor includes a face plate 13 and a power shaft 14 to which there is attached a spur gear 15. Gear 15 meshes with spur gear 16 on shaft 17 of the gear box unit G.

The motor 10 which has an air relief valve 22, is attached to the gear box housing 20 by a plurality of bolts 21 and the housing 20 is in turn attached to the main gear housing 30 by means of bolts, not illustrated. At the base of the gear housing, there is a frame member 31 of any approved type, by which the entire apparatus is supported, the frame 31 being shaped so that it may readily be attached to a conventional "table" or "jack" such as are used for supporting drilling device.

At the motor end of the gear box housing 30, there is provided a bearing retainer 32, carrying a pair of ball bearings 33. The ball bearings 33 serve rotatably to support the shaft 17, which receives power from the motor by way of gears 16 and 15. The inwardly protruding end of shaft 17 is formed with a gear 40, which meshes with a large idler gear 41 on shaft 42. A second smaller idler gear 43 is formed integrally with gear 41 and rotates therewith and meshes with a reversing gear 44.

Within the gear portion 40 of shaft 17, there is a pilot bearing 50, preferably of the needle roller type, which serves to support the end 51 of shaft 55, the other end of shaft 55 being rotatably mounted in a ball bearing race 56, carried on the gearing box housing 30 by means of the bearing retainer 58. The bearing 56 is held in the retainer 58 by means of a member 59, which also contains a grease packing ring 60.

The shaft 55 is splined at 62 and upon it, there is mounted a sliding gear 57 which is illustrated in its "neutral" position in Figure 1. Gear 57 has internal teeth 62, which mesh with the end of gear 40 when the gear is moved to the right in the view Figure 1, and external teeth 63 which mesh with reverse gear 44 when the gear 57 is moved to the left in the view Figure 1. The gear 57 is provided with a groove 65 in which there is a forked shift lever 66, the latter being mounted for movement to the right and to the left (Figure 1) by means of a slide rod 67. The entire arrangement of slide rod 67 and forked rod 66 mounted thereon is arranged to be shifted by means of shift lever 70. Thus the gear shifting apparatus has three positions, namely: forward, reverse and neutral, and the mechanism may be held in either of these positions by the detent mechanism generally designated 71.

The ratio of gearing housed in the gear box G is such that the forward and reverse drives are approximately the same speed for a given motor speed.

The gear box housing 30 is provided with a smoothly faced circular flange 80 at the left as shown in Figure 1, upon which there is mounted a circular rotation plate 81, having an internal T-shaped circular groove 82. Suitable T-shaped bolts, not illustrated, have their heads in groove 82 and protruding through the faced flange 80 of the gear box serve to attach the

rotation plate 80 to the gear box. The rotation plate may be turned with reference to the gear box for shifting the drilling head as will be explained hereinafter.

At the outer end of shaft 55 of the gear box, there is provided a beveled gear 100, which serves to transmit power to a similar beveled gear 101 of the "drill head" generally designated D. The "drill head" consists of a shaped housing generally designated 120, which is provided with a conically surfaced edge 121, which serves to position the drill head co-axially with respect to the shaft 55 of the gear box when the drill head is in operative position on the rotation plate 81. The housing generally designated 120 is provided with a hinge 125 which cooperates with cooperating hinge parts 126 on rotation plate 81. The hinge pin 127 couples the parts 125 and 126 together for hinging action about the pin.

At the opposite side, the drill head is provided with a pair of protruding lugs 130 and 131, between which there is positioned an angularly shaped fastening bolt 133. The bolt 133 is bent at right angles and is preferably mounted upon the lugs 134 of rotation plate 81. The outer end of bolt 133 is provided with a nut 136 and as a result the drill head may be drawn into close engagement with the rotation plate by tightening the nut 136 on bolt 133. The conical surface 121 of the drill head housing which nests in the similar conical surface 122 of the rotation plate thus serves accurately to position the drill head with reference to the rotation plate when the two are drawn together as just described.

In the lower part of the drill head housing, there is provided a bearing plate 140 which serves to mount the ball bearing 141, the latter being held in place by a retainer ring 142 by means of bolts 143. The retainer 143 also serves to carry a grease seal 144. Within the housing 120, there is another ball bearing 150, which is mounted upon the internal housing portion 151, and the bearings 141 and 150 serve rotatably to mount the hollow drill shaft generally designated 160. The drill shaft is provided near its lower end with a flange 161 against which there is pressed a spur gear 162. Above the spur gear, there is pressed the bevel gear 161, which, as previously described, meshes with the gear 100 on the gear box shaft. Below the flange 161 there is mounted the inner race of bearing 141, the race being held in place by a spacing collar and bottom nut 163.

At the upper end of the drill head housing 120, there is provided a recess 170 which contains a bearing retainer 171. The bearing retainer carries a pair of ball bearing races 172, which are held downwardly in place by the bearing retainers 173, which in turn are held by means of an upper cap 174 bolted to the housing 120 by a plurality of bolts 175.

The bearings 172 serve rotatably to support an internally threaded feed nut generally designated 180 which is provided with a lower shoulder 181 against which the inner races of bearings 172 are tightly seated. Above the bearings, there is provided a spacing collar 181 and above these a pair of drive gears 182 and 183. Above the drive gears, there is provided a hand wheel 184; all of these are held in place upon the feed nut by a nut and lock nut 185.

Within the hollow drill shaft generally designated 160 and the co-axially aligned feed nut generally designated 180, there is a threaded hol-

low drill spindle generally designated 200, which is threaded throughout its length (as shown at 201) so as to cooperate with the internally threaded feed nut 180. The hollow drill spindle is also provided with one or more longitudinal key ways 202, which cooperate with internal keys on the hollow drill shaft 160. As a result, the hollow drill shaft 160 serves to rotate the spindle whereas the spindle is advanced or retracted by relative rotation with respect to the feed nut 180.

At the left side of the drill head housing as shown at Figure 2, and as shown in the broken away part of the housing Figure 4, there is provided a feed nut drive arrangement having a shaft generally designated 220. The shaft 220 is rotatably mounted in its lower end in an anti-friction bearing, preferably a needle roller bearing 221, and at the lower end of the shaft there is mounted a gear 222 for rotation with the shaft. The gear 222 meshes with gear 162 as shown in the dotted lines in Figure 2 and serves to rotate the shaft 220 as the hollow drill shaft rotates.

The upper end of the feed nut shaft 220 is likewise mounted in an anti-friction roller bearing 224 which is held in place by a spacing collar 225. Above the spacing collar, there are mounted gears 226 and 227 which are of slightly different diameter, and rotatably mounted with reference to the shaft 220, being held in place upon the shaft by means of a nut and lock nut 228.

The upper half of the shaft 220 is hollow as shown at 230, the hollow portion extending downwardly to 231. Near the lower portion 231, the shaft 220 is provided with oppositely disposed side slots 232, one of which is shown, and at the upper end there is provided a pair of similarly disposed and shown slots 233.

Within the opening 230 of shaft 220, there is mounted a shift rod 240, which is provided with a cross pin 241 near its lower end and with another cross pin 242 at its upper end. The pin 241 serves to attach the shift rod 240 to an external circular rack 243, which is slidably mounted upon shaft 220, the rack 243 being provided with circular teeth 244 which mesh with a shift gear, not illustrated, on shift rod 245. This shift rod 245 is mounted in an external pillow block 246, which is attached to the drill head housing by means of a plurality of bolts 247. At the outer end of the shift rod 245 there is provided a shift handle 248 by which the rod may be rotated with the result that the circular rack 243 is moved upwardly or downwardly on the shaft 220. This shifting of the circular rack 243 and the attached internal shift rod 240 may be accomplished while the apparatus is in rotation or while it is stationary.

The spring detent generally designated 244a is provided between the inner surface of circular rack 243 and the shaft 220. It has a neutral position in which 242 is out of mesh with gears 226 and 227, an upper position in which pin 242 is in mesh with inner notches on gear 227, and a lower position in which pin 242 is in mesh with gear 226.

The gears 226 and 227 are continuously in mesh with gears 182 and 183, respectively, on the feed nut 180. The gear ratio of the gear pair 226-182 is slightly different than the gear ratio of the gear pair 227-183, and with either pair of gears the feed nut 6 is driven at a slightly lesser rate than the spindle.

While only two pairs of feed gears are illustrated, it is obvious that where rock hardness conditions vary widely, require a greater ratio

than is possible with two gears, additional gears and shifting box may easily be added.

The threading upon the drill spindle 200 is "right-hand" and the feed nut 180 is driven at two speeds, depending upon whether gear 226 or 227 is the driving gear. Each of the feed nut drive speeds is less than the spindle speed and as a result, the spindle is accordingly advanced downwardly as it is rotated in the right hand direction. Thus when the spindle is rotated thru 1000 turns, the feed nut may be rotated 994 or 940 turns, which represents one and ten inch feed where the pitch of the spindle thread is six per inch.

At the lower end of spindle 220, there is provided a hexagonal wrench portion 250, which is formed integrally with the drill spindle 200. Beneath the wrench portion 250, there is provided a certain drill rod coupling which has a standard drill rod coupling thread of six threads per inch. In the present apparatus, the threads 201 on the drill spindle are made of the same pitch as the threads 251 for a purpose which will be described below.

Extending downwardly from the rotation plate 81 there are a pair of legs 260, which converge downwardly and are joined together by web 261 at a distance from 30 to 40 inches below the drill rod. At the lower connected ends of the legs 260, there is provided a mechanism for selectively engaging and holding the portion of the drill rod which remains in the hole, all for a purpose to be described.

The mechanism for engaging and holding the drill rod is preferably formed integrally with the downwardly extending legs 260, although in some instances it may be desirable to use separate elements which are attached to the leg portions.

In the illustrated embodiment of this mechanism the two legs 260 are joined together at their lower ends by a unitary casting having cylindrical end portions 262 and 263. Between the cylindrical end portions there is a displaced section having an upper surface 264 and a lower surface 265, (Figure 2), which extends from the plane 266 to the plane 267 as shown in Figure 2.

Each cylindrical end portion 262 and 263 is bored to form cylinders 270 and 271, the cylindrical bores being continued to the lines 272 and 273 respectively. The bore 275 of smaller diameter is continued from the plane 272 directly thru to the plane 273 and thus intersects the outer surfaces of the casting represented by planes 264 and 265 thus leaving an opening 55 through the casting, which is bounded by the lines 281-282 and 266-267. Within the cylinders 270 and 271, there are placed plates 282 and 283, which have square central openings as shown at 285 in Figure 4, each of the plates being 60 attached to its cylinder by means of a bolt 286 each plate is thus prevented from rotation within the cylinder.

Within cylinder 270, there is provided a piston 288, which is preferably made from a cut leather washer. The piston 288 is supported on the reverse side by a metal washer 289 behind which there is a spring 290, which is provided for the purpose of retracting the piston in the direction of the arrow 291. The piston rod 292 is square and thus slides neatly through the square opening 285 of plate 282. The piston is thus prevented from rotating with reference to the cylinder although it is free to move longitudinally.

At the outer end of the piston rod 292, there

is provided a cylindrical head 294, which is of the same diameter as bore 275, and at the free end of the head, there is provided a transverse semi-circular notch 295, having teeth 296. Both the notch 295 and teeth 296 are aligned with the drill spindle. The diameter of the semi-circular portion 295 is the same as that of the drill rod being used.

Cylinder 271 is provided with a similar piston rod and outer cylindrical head for gripping the drill rod, all as described with reference to cylinder 270.

On the side of the cylinders toward legs 260, there is provided a transverse bore 298, which intersects with a bore 297 of cylinder 270 and a bore 299 of cylinder 271. To the bore 297, there is attached an air feed line 300 having a control valve 301 by which air to the cylinders may be turned on and off. The valve 301 is preferably provided with a bleed part to exhaust the air or other motive fluid from the cylinders when the air supply to them is interrupted. The bore 299 is stoppered by means of screw plug 302 and the bore 298 is likewise stoppered by means of plug 303. The outer ends of the cylinders 270 and 271 are provided with cylinder heads 305 and 306 respectively, which are attached to the cylinders by means of a plurality of cylinder bolts 307. A gasket 308 is preferably provided between the cylinder head and the cylinder body.

At the upper end of the drill spindle 200, there is provided a swivel water connection generally designated 320, to which there is attached a water hose 321. This swivel connection may be of any acceptable variety capable of delivering water to the spindle while the spindle is rotated at high speeds.

In Figures 2 and 4, the portion of the drill rod which extends into the hole being bored is illustrated at 330, the surface of the rock or earth being shown at 332.

Operation

In the operation described below, it will be assumed that the drill is mounted over a surface being bored and that the drill spindle coupling portion 250 is closely adjacent the drill head housing 120, that the drill rod is coupled to the drill spindle at threads 251, and that the drill is not rotating, but is ready for the drilling operation. It is assumed further that water is being supplied to the swivel joint 320 and therethrough to the diamond bit, not illustrated, at the lower end of the drill rod.

1. In order to initiate the operation, the operator shifts the gear box handle 70 into the "forward" drive position in which gear 57 is located to the right as shown in Figure 1 into engagement with gear 40. The handle 248 is then moved to one or the other of its extreme positions which shifts the pin 242 into engagement with one or the other of the feed drive gears 226 or 227 thereby providing a feed drive through gears 182 and 183 to the feed nut 180.

The valve 301 of the drill rod assembly is moved to the "off" position and springs 290 within cylinders 270 and 271 move their respective pistons to the retracted position with the result that the cylindrical drill rod engaging and holding heads 294 are moved out of engagement with the drill rod.

The throttle valve 12 of engine 10 is then opened and the drill begins to rotate and is fed downwardly, the drilling being continued until

the spindle has approached the limit of its downward travel at which time the hexagonal end 250 of the spindle will be closely adjacent the cylinders 270 and 271.

5 2. The air supply to motor 10 is then discontinued, and air valve 301 is moved to the "on" position with the result that pistons 288 are moved to their operated position. This forces the heads 294 into engagement with the portion 330 of the drill rod in the hole and prevents any rotation or longitudinal movement of the part of the drill rod within the hole. The shaft handle 70 is then moved to the reverse position, the feed shaft 245 is moved to the neutral position by means of handle 248 and the motor 10 started by opening valve 12. At the same time, the operator firmly grips hand wheel 184 so as to prevent the feed nut 180 from rotating. The spindle 200 is accordingly rotated towards the machine, and since the threads 251 of the coupling to the drill and the threads 201 of the feed screw are of the same pitch, the spindle 200 is screwed upwardly and out of connection with the drill rod 330 without longitudinally disturbing the drill rod. This is important inasmuch as it is undesirable on the one hand to force the diamond bit into engagement with the end of the hole and likewise undesirable to retract the drill rod and attached diamond bit from engagement into the bottom of the hole. When the threaded coupling 251 is disconnected, the drill rod is rapidly withdrawn due to the fact that at the time the operator is holding the feed nut 180 stationary. With the feed nut stationary the upward movement of the spindle is very rapid as compared with the down feed of the spindle during drilling operations since the differential of speed between spindle and feed nut is at this time equal to the spindle speed. By way of comparison it may be noted that when the feed nut is rotated during drilling there is only a slight differential of speed between the spindle and feed nut.

3. As soon as the spindle 200 is fully retracted, 45 a fresh section of drill rod is screwed on to the drill rod 330, which is at the time held tightly in place due to the action of cylinders 270 and 271 which are in the operated condition. The fresh section of drill rod may have a short space between its upper end and the then retracted screw coupling 251, and in order to bring down the spindle into engagement with the upper end of the fresh section of drill rod, the operator may merely turn the hand wheel 184 if the distance is small and thus bring the threads of the spindle 50 into alignment with the threads of the newly added section of drill rod. Preferably, however, the operator shifts handle 70 into the "forward" drive position and the throttle 12 of motor 10 is slightly opened so as slowly to rotate the motor with the result that the spindle is brought downwardly into engagement with the newly added drill rod section. During this "running down," as in the "retracting" operation previously described, the operator holds wheel 184 of the feed nut. In this mode of operation the threads 251 may run directly into the threads of the newly added section of drill rod since by holding the feed nut 180 stationary the downward movement of the spindle 200 through each turn is equal to the pitch of threads 251 in the then stationary drill rod. Due to this correspondence in pitch, there is no tendency to displace the drill rod 330 in the hole either to lift the same from the end of the hole nor is there

a tendency to force the drill rod against the bottom of the hole with excessive pressure.

At this juncture it may be explained that excessive pressure on the drill rod may ruin the diamond bit and may even lift the drilling apparatus due to the pressure on the bit. When the latter occurs the alignment of the drilling apparatus with the hole is changed, all with undesirable consequences. Likewise, lifting the bit off the bottom of the hole is undesirable since it must then be run down into contact with the hole before drilling can be resumed.

4. After the threaded coupling 250 has been screwed into the fresh section of drill rod as previously described, the shift handle 248 of the feed screw drive is moved into one or the other of its operated positions and with the gear box lever 10 already in the "forward drive" position and valve 301 and cylinders 270 and 271 moved to the "off" position drilling may be resumed by opening the throttle valve 12 of motor 10.

Drilling is then continued as described under paragraph 1 above.

The aforementioned operation may be carried out with equal facility regardless of whether the drill is being operated in a vertical position or at some angle other than vertical since in any position the drill rod engaging and holding arrangement is accurately positioned and aligned with respect to the spindle and drill rod by means of legs 260.

Many obvious variations may be made in the apparatus herein described without departing from the spirit of the invention. Thus, in some instances, it is desirable to use a hydraulic feed mechanism in place of the mechanical feed screw mechanism here described, and in some instances it is desirable to use a reversible electric, or pneumatic motor in place of the engine M and reverse gear box G here described. Likewise, the illustrated mounting of the drill head D may be widely varied to meet the exigencies of particular installations and the method of mounting the drill rod engaging and holding arrangements (cylinders 270 and 271) may be changed to suit any particular design. Thus cylinders 270 and 271 need not be pneumatic but may be a hydraulic mechanism operated, for example by a foot pressure on a master cylinder, or a mechanical device for accomplishing the desired result of holding the drill rod while the fresh section of drill rod is being added, may be used.

These and many other obvious variations will be apparent to those familiar with the art and may be made without departing from the broad scope of the invention claimed.

What I claim is:

1. A drilling device comprising drill spindle means having a feed screw means thereon, motor means for driving the spindle means in either direction, feed nut means, hand means connected with the feed nut for rotating the feed nut by hand and disconnectable drive means for rotating the feed nut means from the spindle means during drilling.

2. A drilling machine comprising a spindle, means including screw threads on said spindle and cooperating feed nut means for advancing said spindle through a predetermined distance, a drill rod axially aligned with said spindle, and means including a screw threaded connection having threads of the same pitch as those on the spindle for connecting the drill rod and spindle.

3. A drilling machine comprising a spindle, 75

means including screw threads on said spindle and cooperating feed nut means for advancing said spindle through a predetermined distance, a drill rod axially aligned with said spindle, 5 means including a screw threaded connection having threads of the same pitch as those on the spindle for connecting the drill rod and spindle and means on said machine for engaging and holding the drill rod.

4. A drilling machine comprising a spindle, means for rotating the spindle in either direction, means including threads on said spindle and a cooperating nut means for axially moving the spindle through a predetermined distance in either direction as it is rotated, a drill rod arranged in line with said spindle and a screw threaded joint for connecting the drill rod and spindle end to end, the threads of said joint being of the same pitch as the threads on said spindle, disconnectable means for rotating the feed nut means as the spindle rotates to axially move the spindle, and hand means for controlling the rotation of the feed nut means when said disconnectable means for rotating is disconnected.

5. A drilling machine comprising a spindle, means for mounting said spindle for movement through a complete circle of radial positions, said movement being about an axis at right angles to the axis of said spindle and through said spindle, means for rotating said spindle about its own axis, means for moving said spindle axially through a predetermined distance as it rotates about its own axis, a clamp means mounted on 30 said means for mounting said spindle, said clamp means being positioned axially with respect to said spindle beyond the limit of axial movement of the spindle.

6. A drilling machine comprising a frame, a 40 spindle mounted for rotation and for axial movement with respect to said frame, means for rotating the spindle, means for axially moving the spindle including threads on said spindle and a cooperating feed nut, means for rotatably mounting said feed nut, mechanical drive means for 45 rotating the feed nut at a slightly different speed than the speed of said spindle, means for interrupting said mechanical drive means, and hand wheel means connected to said feed nut for rotating the same.

7. A drilling apparatus comprising a spindle, a 50 drill head mounting the spindle for rotation and for advancing and retracting axial movement through a limited path, power means for rotating and axially moving the spindle, means 55 mounting the drill head for free turning movement about a drill head axis which is through the spindle and at right angles thereto, said drill head having a frame extension thereon and a plurality of clutch jaws mounted on the frame 60 for movement toward and from the drill spindle axis, said jaws being positioned beyond the limit of advancing movement of the spindle, whereby the jaws may grip a drill rod attached to the spindle, in any radial working position of the 65 drill head.

8. A drilling device comprising drill spindle means having a feed screw means thereon, motor means for driving the spindle, feed nut means, hand wheel means connected with the said nut for rotating the feed nut by hand, and disconnectable drive means for rotating the feed nut means from the spindle means during driving.
